(57) **CLAIM**

The ornamental design for a bassinet for baby carriage, as shown and described.

DESCRIPTION

Bassinet for baby carriage

1.1 is a front, top, and left side perspective view of a bassinet for baby carriage showing our new design;

1.2 is a front elevation view thereof;

1.3 is a rear elevation view thereof;

1.4 is a left side elevation view thereof;

1.5 is a right side elevation view thereof;

1.6 is a top plan view thereof; and

1.7 is a bottom plan view thereof.

(Continued)

The broken lines in the drawings depict portions of the bassinet for baby carriage that form no part of the claim.
